SEPTIC TANK

Milton S. Butler, South Braintree, Mass.

Application June 10, 1947, Serial No. 753,728

2 Claims. (Cl. 219—6)

1

This invention relates to tanks for sewage disposal and especially to a tank of this type in which a plurality of slabs or blocks of a material such as concrete are arranged in interlocking relation to form the sides of the tank body and other related drainage structures.

Septic tanks, cesspools and similar devices for sewage disposal are subject to overflow and failure and in most cases may be used for a limited time only before they require cleaning. A common difficulty especially in septic tanks is the tendency for clogging or stoppage to occur around the baffle plate employed in these devices. When this occurs in a closed tank, sewage backs up in the inlet pipe, requiring troublesome and expensive repairs.

The device of the present invention avoids the difficulties noted to a large extent by eliminating the use of baffle plates; by utilizing a greater soil drainage area; and by constantly providing for a reserve drainage area to which access may be had whenever it is found necessary. With this arrangement, sewage tank facilities are made possible of exceedingly long life, and substantial savings in the cost of material and installation are achieved. An important feature in this connection is the combination with an open bottom tank structure of a plurality of laterally extending drain chambers which are connected to a common outlet by separate conduits, each of which has its extremity extending into a respective chamber. The tops of the drain chambers are removable at points directly above the extremities of the conduits. Coacting with the covers is a plug member which is removably secured in one conduit extremity and interchangeable with the other conduit extremity. This arrangement provides for one of the drains constantly being held out of operation in reserve for a further use when needed.

Another feature of the invention is a special slab element construction from which side walls may be made up. Some or all of the slab elements may include separator members formed therein so that a separation of solid material from liquid may be effected, with the result that the conventional baffle plate of a septic tank is eliminated.

Another feature of the invention is the provision of a novel type of inlet pipe which is combined with the sectional tank in such a manner as to provide for installation at varying angles. The inlet pipe is further formed with a special removable cleanout cap which greatly facilitates clearing inlet pipes and sewage conduits running

between the tank and the start of the conduit lines, or at other points. These and other novel features and objects of the invention will appear from the following discussion.

- 5 In the accompanying drawings:
- Fig. 1 is a perspective view illustrating frame members utilized in forming the tanks of the invention;
- Fig. 2 is another perspective view showing a section of a tank partly assembled on the frame member;
- Fig. 3 is a plan view of the sewage tank of the invention;
- Fig. 4 is a vertical cross-section;
- Fig. 5 is a detail view of laterally extending drain means;
- Fig. 6 is a perspective view of an inlet pipe employed with the tank of the invention;
- Fig. 7 is a detail plan view;
- 20 Fig. 8 is a perspective view of the special slab construction utilized in forming the tank of the invention; and
- Fig. 9 is a vertical cross-sectional view of a slab.
- 25 Referring more in detail to the drawings, numerals 10, 12, 14, 16, 18, 20 indicate frame elements which may be arranged in the manner suggested in Fig. 1, to constitute a base for the remainder of the tank structure of the invention. The frame elements are designed to be laid directly in a tank opening which has been dug in the earth to leave an open bottom area 22. Upon the frame members, snugly fitted against the raised inner edges thereof, are mounted upright slabs of concrete or other material, such as noted by numeral 24. The slabs are preferably braced apart by means of transverse members 25 and longitudinal members 25a. As shown in Fig. 2 of the drawings, the slabs are formed with opposite upper shouldered portions on which the transverse members are received. The transverse members are in turn formed with upper relieved ends on which are supported the longitudinal members 25a as shown in Fig. 2. The longitudinal members lie against adjacent slabs and are chosen of a width or thickness which allows them to project above the upper edges of the slabs and thus provide vertical supporting edges for receiving thereagainst the lower portions of the next row of overlapping slabs. Fig. 2 indicates the use of the slabs to form a tank of any desired height, by superimposing the slabs one upon another. Similarly they may be used in larger numbers to build tanks of varying widths and lengths.

In Figs. 3 and 4, are indicated a plan view and a vertical cross sectional view respectively of a tank including two tiers of slabs mounted one upon the other, with there being employed four of the slabs 24 in each tier. Located above these slabs are cover members 26, one of which may be formed with an opening 28 in which is arranged an inlet pipe 30, preferably of a square cross section, such as may be formed by casting or molding cementitious materials. The inlet pipe is of a size less than the diameter of the opening 28 so that when installed it may be swung about into any position of angularity which may be found necessary to avoid stones, ledges, or other obstacles in installing the tank at a desired point. After a suitable position for the inlet pipe has been determined, it can be fixed in place by inserting cement or other material between itself and the edges of the opening 28, and such packing or sealing materials can be removed at such times as it may be found necessary to remove the inlet pipe and the cover.

Numerical 32 denotes a removable cleanout cap of triangular shape, more clearly shown in Fig. 6, which constitutes a section of the corner of the pipe 30. This arrangement provides ready accessibility to openings 34 and 36 (Fig. 6) of the two sections of pipe 30, where it may be desired to remove obstructions from either of these pipe sections. The cap 32 may, if desired, be detachably secured by means of a pin 42 which is passed through openings 43 and 46 in the pipe and opening 44 in the cap. To further secure the cap in place, I have provided a recessed shoulder 48 upon which a corresponding recessed edge of the cap may be disposed. It is pointed out that with an inlet pipe of this character, it is entirely feasible in the event of a clogged sewerage system, to overcome the difficulty at once simply by digging up the cover, removing the cap and inserting a wire element through the pipe 30. Thus a great deal of unnecessary labor may be avoided. The cap also may be employed with an outlet pipe 60 on the opposite side of the tank.

Sewage enters the tank from the pipe 30 and passes down into the bottom of the tank, rising to a level where it passes out through the sides of the slab members 24 and eventually discharges from the outlet pipe 60. Passage of sewage through the side walls is provided for by separator members 50 which constitute inner and outer conduits through which sewage may pass to the soil surrounding the slabs 24. By this arrangement, the use of a conventional baffle plate can be avoided since movement of solids is restricted by the inner conduit, and liquids are dissipated through the outer conduit and the open base of the tank.

It will be noted that each separator is formed with a closed upper inner side 52, and a closed upper outer side 54. The latter affords protection against soil entering the separator and blocking the passageway, while the former maintains the bacteria mat out of communication with the opening through the slab. It will also be observed that openings 55 in the side of the outer conduits 50 are below the openings 57 in the intermediate slab portion, so that a baffle effect is thus secured by each separator. The use of the separator element may be desired in all of the slabs or only a part of the slabs may be so equipped, and provides access to surrounding soil regions thus increasing the seepage area to a very great extent.

Figs. 3 and 4 illustrate a two-way conduit member 58 which connects with the outlet pipe 60 inserted into the tank. The two-way conduit has two outer extremities 62 and 64 which communicate with drainage chambers 66 and 68, also made up of interlocking slabs 65 such as those shown in Fig. 5. It is intended that these slabs also may have separator elements. Fitted in the extremity 64 is a plug member 70 which is adapted to be removed at such time as the drainage chamber 66 has become filled. The plug at this time is removed from the empty chamber 68 and inserted in the conduit end 62, preventing further flow into this area while opening a passageway into the alternate chamber 68. Each chamber is equipped with removable covers 80 to facilitate the interchange of the plug 70. Alternating the plug can be repeated as many times as desired to continually maintain a relatively free drainage area to which the tank is connected.

The alternate chamber feature, when combined with the slabs having separator elements, provides an exceedingly long-life sewerage system by which sudden overloads may be handled satisfactorily with an unusually large seepage area being contacted.

I claim:

1. An improved sectional type sewage tank construction for use in a sewage excavation, comprising a tank body having vertical side walls and end walls extending therebetween, said side and end walls adapted to be located against the vertical surfaces of the sewage excavation and to be externally supported thereby, said side walls including a plurality of courses of pre-formed slab elements located one above another, the slab elements of each course being arranged in an upright position with adjacent vertical edges lying in abutting relationship, each of said slab elements of the said side walls being formed with upper rabbeted corners, a plurality of transverse brace members constructed and arranged so as to extend between the sides of the tank and supported on the rabbeted corners of said side wall slab elements, each of said transverse brace members being rabbeted to form relieved ends and intermediate shoulders which project above the relieved ends, said transverse brace shoulders occurring in spaced relation to inner wall surfaces of the tank to define slots, a plurality of longitudinal brace members mounted in the slots on the relieved portions of the transverse brace members and snugly received between the side wall slabs and the transverse brace shoulders to hold these members in locked relationship to one another, said braces at their outer surfaces constituting retaining edges against which succeeding courses of said side wall slabs may be laterally supported, said tank structure further including inlet pipe means connected to the tank, said inlet pipe consisting of a unitary member which includes two conduit sections meeting one another at an angle, the unitary member further presenting a corner section angularly disposed and adjustably secured at the junction of the two conduit sections, the corner section when separated from the adjoining inlet pipe portions providing an aperture which communicates with openings of both conduit sections.

2. An improved sectional type sewage tank construction for use in a sewage excavation, comprising a tank body having vertical side walls and end walls extending therebetween,

said side and end walls adapted to be located against the vertical surfaces of the sewage excavation and to be externally supported thereby, said side walls including a plurality of courses of preformed slab elements located one above another, the slab elements of each course being arranged in an upright position with adjacent vertical edges lying in abutting relationship, each of said slab elements of the said side walls being formed with upper rabbeted corners, a plurality of transverse brace members constructed and arranged so as to extend between the sides of the tank and supported on the rabbeted corners of said side walls slab elements, each of said transverse brace members being rabbeted to form relieved ends and intermediate shoulders which project above the relieved ends, said transverse brace shoulders occurring in spaced relation to inner wall surfaces of the tank to define slots, a plurality of longitudinal brace members mounted in the slots on the relieved portions of the transverse brace members and snugly received between the side wall slabs and the transverse brace shoulders to hold these members in locked relationship to one another, said braces at their outer surfaces constituting retaining edges against which succeeding courses of said side wall slabs may be laterally supported, said tank structure further including a base having inner retaining edges for supporting the bottom portions of said side walls, a cover including horizontally disposed slabs received on the side walls, inlet and outlet pipes connected to the tank construction, said outlet pipe including a dual conduit, drain members

5

connected to the extremities of the dual conduit, and an interchangeable plug member adjustably secured in one of the dual conduits.
